UNITED STATES PATENT OFFICE

HARRY CHIRELSTEIN, OF CHICAGO, ILLINOIS, ASSIGNOR TO BELMONT CLOCK COMPANY, OF CHICAGO, ILLINOIS, A CORPORATION OF ILLINOIS

DESIGN FOR A CLOCK CASE

Application filed September 25, 1931. Serial No. 41,223. Term of patent 3½ years.

To all whom it may concern:

Be it known that I, HARRY CHIRELSTEIN, a citizen of the United States, residing at Chicago, in the county of Cook and State of Illinois, have invented a certain new, original, and ornamental Design for a Clock Case, of which the following is a specification, reference being had to the accompanying drawing, forming a part hereof.

The figure is a perspective view of a clock case showing my new design.

I claim:

The ornamental design for a clock case, substantially as shown.

HARRY CHIRELSTEIN.
